UNITED STATES PATENT OFFICE.

MICHAEL F. DAVORAN, OF CINCINNATI, OHIO, ASSIGNOR TO THE CRANE & BREED MANUFACTURING COMPANY, OF CINCINNATI, OHIO, A CORPORATION OF OHIO.

BURIAL-CASKET HARDWARE.

1,027,106.

Specification of Letters Patent.

Patented May 21, 1912.

Application filed January 4, 1912. Serial No. 669,340.

To all whom it may concern:

Be it known that I, MICHAEL F. DAVORAN, a citizen of the United States of America, and a resident of Cincinnati, in the county 5 of Hamilton and State of Ohio, have invented a certain new and useful Improvement in Burial-Casket Hardware, of which the following is a specification.

This invention relates to hardware especially adapted for use on the surface of burial-caskets, or, more particularly, to the name-plates and handle-lugs used on such receptacles, and its object is to provide a name-plate and a handle-lug with a series 10 of slits or perforations that have between them bars or gratings that adapt the device to the interlacing of a ribbon, or like flexible material that harmonizes in color with that of the metal or material composing 15 said name-plate and handle-lug and imparts a pleasing and softening effect, as fully hereinafter described in detail and particularly pointed out in the claim.

In the accompanying sheet of drawings, 20 Figure 1 is a plan view of a name-plate for a burial-casket showing my invention in one of its preferred forms and Fig. 2 is a cross-section taken on the dotted-line α , α , of Fig. 1.

30 1 indicates the body portion of a name-plate for the desired inscription.

2 indicates the base portion; 3, 3 the opposite ends that form side columns or panels on said body portion and base portion; 4, 4

35 shield-heads surmounting the upper ends of said side columns; and 5 an arched portion surmounting said body portion and terminating at said side shield-heads. 6 indicates a central shield or key-stone member in said arched portion 5. 7 indicates each one of a series of parallel, spaced bars forming a grating along the arched portion 5 between said central key-stone member and said shield-head members.

40 45 8 indicates a flexible strip shown in Fig. 1 as being interlaced through the slits or elongated perforations between the bars 7 of the grating 5, and preferably with its opposite ends extending and draping beyond 50 the shield-heads 4, 4, as shown at 9, 9. Of

course, said draping-ends 9 can be omitted and the strip or ribbon 8 terminate at any suitable point back of the shield-heads 4. Instead of using the said draping-ends 9, suitable tassels can be used for the handle-lugs on the side of the casket and attached at the opposite ends of said strip or ribbon 8 so that they shall gracefully hang. The ribbon or strip 8 is adapted to be of any suitable hue or color and it is intended that 55 such hue or color shall correspond or harmonize, or even contrast with that of the metal composing the name-plate or the handle-lug. It is obvious that unlimited fancy or choice can be duly met in the 60 variety of combinations of colors of ribbon and metal to which my invention is adapted. The ribbon or strip may be either flexible 65 so as to duly interlace through the perforations or the grating, or it may be a stiff 70 one adapted to be placed back of the grating and not interlaced at all, but the effect of the stiff one would not be as good as that of the flexible form that has a more pleasing 75 and softening effect, and does not otherwise unduly ornament the casket. The ribbon or strip can be drawn taut to impart a smooth or plain effect, or it may be inserted and left somewhat loose and puffy by having it a little wider than the width 80 of the slits or perforations and thereby impart a purled effect that is shown in front elevation in Fig. 1 and in cross-section in Fig. 2.

Instead of interlacing the ribbon just as 85 shown, it may be passed between alternate single bars, or three successive bars could be hidden and then but a single bar displayed, so as to expose more or less of the ribbon or more or less of the bars as desired. 90

I claim:

A burial-casket name-plate or handle-lug having a grating or perforated part and a ribbon, tape or like textile fabric adapted to be placed back of or interlaced through 95 said grating or perforated part.

MICHAEL F. DAVORAN.
